UNITED STATES PATENT OFFICE.

SOLOMON H. GOLDBERG, OF CHICAGO, ILLINOIS, ASSIGNOR TO THE HUMP HAIRPIN MANUFACTURING COMPANY, OF CHICAGO, ILLINOIS, A CORPORATION OF WEST VIRGINIA

HAIRPIN BOX.

1,424,471.

Specification of Letters Patent. Patented Aug. 1, 1922.

Application filed April 18, 1917. Serial No. 162,262.

To all whom it may concern:

Be it known that I, SOLOMON H. GOLDBERG, a citizen of the United States, residing in the city of Chicago, county of Cook, and 5 State of Illinois, have invented certain new and useful Improvements in Hairpin Boxes, of which the following is a specification.

This invention relates to improvements in boxes or containers for hairpins and has 10 among its salient objects to provide a construction in which the hairpins are mounted in a supplementary container by which they can be readily pushed into view upwardly so that they can be more readily removed 15 and can then be pushed back into the box so that they can be enclosed; to provide a construction in which hairpins of various sizes can be mounted in the same container and still be readily accessible in the manner just 20 described; to provide a construction which is economical of manufacture, which makes an attractive package and in which the hairpins are, at all times easily accessible and in general to provide an improved construction 25 of the character referred to.

In the drawings:

Fig. 1 is a vertical sectional view of the box, the top shown as open.

Fig. 2 is a perspective view with the top 30 open but the supplementary container entirely enclosed in the outer container.

Fig. 3 is a view similar to Fig. 2 but showing the supplementary container raised to permit of the hairpins being more readily 35 removed.

Fig. 4 is a detail view showing the manner of forming the inner box or container.

Fig. 5 is a detail view showing the manner of forming the outer box.

40 Referring to the drawings, 1 designates the side walls and 2 the end walls of the outer box, which are preferably formed of a single piece of cardboard, paper, or other flexible material having its edges overlapped 45 as shown at 3 and cemented together. The top of the outer container is closed by end flaps 4 and 5 and a side flap 6 having a confining tongue 7, which fits within the adjacent side wall 1 when the top is closed. The 50 bottom is similarly closed with end flaps 8 and 9 and the side flap 10, having a confining lip 11 similar to the tongue 7. The central portion of the side flap 10 is provided with a suitable aperture 12, which registers 55 with the cut-away portions 13 and 14 of the

end flaps 8 and 9 when the bottom is closed. These cut-away portions and the aperture 12 serve as a finger opening for the purpose hereinafter described.

Describing now the inner container or 60 compartment, it comprises side members 15 and 16, end members 17 and 18. The bottom of the inner compartment is closed by means of end flaps 19 and 20 and a side flap 21 which extends across the entire bottom of 65 the inner container and is provided with a locking tongue 22, which fits within the adjacent side wall. If desired, the front side wall 15 of the inner compartment is cut away or made shorter than the back wall 16 70 in order that the pins may be made more accessible. The top of the inner compartment is open as there is no necessity of providing it with a closure. The inner container is provided with a plurality of compartments 23, 24, 25, etc., these compartments being formed by a pair of interlocking 75 partition members 26 and 27, which are notched as shown at 28 so as to interfit with each other.

80 The compartments having been filled with pins of various sizes, the inner container is then seated in the outer container and the ends of the top end of the latter closed. The filled box is now ready for shipment. When 85 it is desired to use the hairpins, it is only necessary to first open the top of the outer container and then push up on the inner container by inserting the thumb or finger through the opening in the bottom of the 90 outer container. This pushes the hairpins into view where the desired pin can be more readily removed. When the pins desired are taken out of the container, the inner container is then pushed back and the top 95 closed.

The outer container is preferably formed of a single piece of paper or cardboard, or other flexible material scored in order to bend it easily. The inner container is also 100 formed in the same way. This is advantageous in that it permits them to be stamped out of a blank sheet and then bent along the proper lines to form the flaps and walls.

105 The particular form and style of the box may be varied to suit the individual case. The invention is not limited to the details of construction shown.

I claim as my invention:

110 1. A hairpin box, consisting of an outer

container, formed of a single sheet of paper, said container being closed at each end by movable flaps, the flaps at the lower end being cut away to form a finger aperture, and 5 an inner container, similarly formed of a single sheet of paper, and having a closed lower end and slidably fitted within the outer container and adapted to hold compartments and be raised by inserting the 10 finger through said aperture in the outer container.

2. A hairpin box, consisting of an outer

container, formed of a single sheet of paper, said container being closed at either end by movable flaps, the flaps at the lower end being cut away to form a finger aperture, and 15 an inner container, similarly formed of a single sheet of paper, and having a closed lower end slidably seated within the outer container and adapted to hold compartments 20 and be raised by inserting the finger through said aperture, said inner container being divided into a plurality of compartments.

SOLOMON H. GOLDBERG.
